ATTORNEY

UNITED STATES PATENT OFFICE.

THOMAS SHAW, OF PHILADELPHIA, PENNSYLVANIA.

DISINFECTING-CANDLE.

SPECIFICATION forming part of Letters Patent No. 281,798, dated July 24, 1883.

Application filed March 26, 1883. (No model.)

To all whom it may concern:

Be it known that I, THOMAS SHAW, of the city and county of Philadelphia, Pennsylvania, have invented a new and Improved Disinfecting-Candle; and I hereby declare the following to be a full, clear, and exact description of the same.

My invention consists in combining any suitable disinfecting materials with tallow, wax, or other combustible material, for the purpose of constructing a candle of easy ignition and sure combustion to vaporize and combine with oxygen, sulphur, or other disinfecting materials, for the purpose hereinafter explained.

The object of the invention is to furnish a cheap, safe, and ready means of disinfecting sick-chambers to prevent the spread of contagious diseases, and as a preventive and possible cure of contagious diseases that are propagated by spores and animalcules floating from the sick, or from foul cesspools, drain-pipes, &c.

In order to enable others to use and practice my invention, I will proceed to describe its construction and operation.

The candle, of configuration of an ordinary candle, as shown in drawing, is constructed, primarily, of sulphur and tallow, in proportions of six of tallow or wax to one of sulphur, by weight. The ordinary flowers of sulphur or pulverized sulphur is mixed with melted tallow, in which material it is held by mechanical suspension, in which condition it is poured into the usual candle-mold provided with the ordinary cotton wick, which fashions it into the candle shape, and after it is withdrawn from the mold it can be treated as an ordinary candle in the usual manner. The effect of the combustion of this candle is to generate in a moderate and permissible degree sulphurous vapors that permeate every part of the room in which the candle is placed, and ultimately the entire house, or wherever the air circulates from said room, in a manner

sufficient that no suffocating odors are noticed by the occupants, while the room or house can be disinfected and contagious diseases be warded off by the annihilation of the spores and animalcules with said sulphurous vapors. These effects can be modified and possibly augmented by the addition of other chemical agents.

The purpose of this improved candle is to provide a ready means of disinfecting by chemical combustion in a safe and practicable manner, to be employed in every household by those unskilled in the chemie arts without danger and at trifling cost, and to cause the combustion to extend over a prolonged period, to avoid the dangers and impractical features of a too rapid combustion.

It will be evident that the sulphur or other chemicals can be combined with various hydrocarbons and in varied proportions, and that the candles can be fashioned into various shapes without any alteration in the result. I therefore do not wish to confine myself to any exact proportions or shape.

I am aware that it has been proposed to combine sulphur with paraffine and other hydrocarbons in laboratory operations, and the combination was to be effected by heating the same and causing the ultimate fusion of the two substances; but my invention is distinguished by the fact that I secure a combustion of the sulphur, and that such combustion is slow, continuous, and uniform.

I claim—

As a new article of manufacture, a candle having a carbonaceous body and a wick, and sulphur or other disinfectant combined with the carbonaceous matter of the candle, whereby to secure the constant uniform evolution of disinfecting gas as the candle is consumed, substantially as set forth.

THOMAS SHAW.
